P. C. JAMES,
HOG DOOR AND GATE.
APPLICATION FILED MAR. 14, 1916.

1,220,636.

Patented Mar. 27, 1917.

UNITED STATES PATENT OFFICE.

PERRY C. JAMES, OF SCIOTA, ILLINOIS, ASSIGNOR TO GEORGE G. BAYNE, OF BUSHNELL, ILLINOIS.

HOG-DOOR AND GATE.

1,220,636.

Specification of Letters Patent. Patented Mar. 27, 1917.

Application filed March 14, 1916. Serial No. 84,194.

To all whom it may concern:

Be it known that I, PERRY C. JAMES, a citizen of the United States, residing at Sciota, in the county of McDonough and 5 State of Illinois, have invented a new and useful Hog-Door and Gate, of which the following is a specification.

My invention relates to a combined door and gate which is especially adapted for use 10 in connection with hog-houses, but which it will be evident, as the nature of the invention is more fully disclosed, will be equally as efficient when used in other capacities.

The principal object of my invention is to 15 provide a swinging door which is provided with an adjustable gate.

Another object is to provide a novel gate-supporting latch operable either by the fingers of the operator, or by a cord, from a 20 distance.

Other objects will presently appear; some of these will be obvious, others specifically pointed out.

The general object of the invention may 25 therefore be said to be to improve the construction and increase the utility and efficiency of devices of this character.

In the accompanying drawing:

Figure 1 is a perspective of a device embodying my improvements, constructed and arranged in the best way now known to me, shown as in operative position in a building; and

Fig. 2, an enlarged sectional detail of the 35 gate-operating latch.

Referring to each element and, where necessary, to each part thereof, by a distinguishing reference numeral, uniformly employed, and considering the drawings in detail, 2, 2' indicate door-casings in the nature of frame-posts, to which are secured partitions 3, 4, 5. 7 and 9 denote hinge butts secured by screws 10 to the post 2 and partition 4.

11 designates a door-frame preferably formed of a single piece of L-shaped angle-iron the branches of which are designated by 12 and 13. The joint or union of the ends is preferably effected by acetylene-torch welding. 14, 14 designate hinge-leaves connected by pintles 15' with the butts 7 and 9, the leaves serving also as braces for the frame 11. 15, 15 are corner-braces. 16 designates an intermediate hinge.

18 designates an eye the inner end of

which is riveted into a countersink (which, as it is an old construction, is not shown) in the distant side of the web 12 of the frame 11. 19 is a hook-receiver the lower portion of which is U-shaped and provided with an 60 aperture 20. 21 designates a hook, having at one end an eye 22 engaged with the eye 18 and at its other end a bent end 23 adapted to engage the aperture 20.

25 indicates a gate the vertical edges of 65 which slide between the side pieces of the frame 11. It is restrained from forward displacement by the arms or branches 12 and from rearward displacement by guide-clips 26 each of which is secured to the gate with 70 its outer end bent to overlie the adjacent branch 12. Together with the frame 11 the gate 25 constitutes a door which may be swung upon the hinges to permit the passage of an attendant, for cleaning out lit- 75 ter, etc.

Fixed to and depending from the upper cross-bar of the frame 11 is a toothed rack 27. 28 indicates a roller or pulley mounted on gudgeons 29 which seat in bearings in a 80 bracket 30 also fixed to said cross-bar.

31 indicates a latch-releasing pull-rod to the upper end of which is secured one end of an operating-cord 32, the flight or run of which passes over the pulley 28 and the 85 other end of which may be run to any distant place in the building, whereby the gate may be operated by an attendant at a distance therefrom. The rod 31 passes through an aperture in a bell-crank releasing-lever 33 90 fulcrumed at 34 in a latch-casing 35 secured to the gate and its lower end then formed into a head 42. 36 indicates a gate-locking latch the locking end 37 of which is cut away at 38 to permit the passage of the rod 95 31 and the inturned lower end of which is pivoted on a pintle 39 secured in and crossing the casing 35. The free end of a bow spring 40 bears against the swinging end of the latch 36 to cause its terminal 37 to engage the teeth of the rack 27. Said spring is fixed to the casing 35 by rivets 41.

Suppose it to be desired that a sow be confined in the pen formed in part by the partitions 3 and 4, but that her pigs be permitted to pass therefrom. The operator by drawing on the cord 32 and thereby the rod 31 will trip the bell-crank 33 to cause its upper arm to bear backward on the swinging portion of the latch 36 and thereby free 110

its terminal or latch-point 38 from the rack-tooth with which it was engaged. If he continues to draw on the cord he will hold said latch in said disengaged position and 5 will simultaneously elevate the gate to the position desired, whereupon release of the cord will permit the spring 40 to react and throw the latch-point 37 into one of the notches of the rack 27.

10 If it be desired to lower the gate the operator will exert only sufficient energy to overcome the resistance of the spring 40, whereupon the gate will fall by gravity, and when it has reached the position desired, 15 release of the cord will permit the spring 40 and latch 36 to operate as above described.

19 If there be no necessity for opening the gate from a distance the cord 32, rod 31, 20 pulley 28 and bracket 30 may be dispensed with. The operator may then grasp the casing 35 and with his finger tips press the latch 36 and thereby the spring 40 back, whereupon (still holding the latch back) 25 he will, by means of the casing 35, raise or lower the gate to the position desired. The dotted lines *a* show the upper, and the dotted lines *b* the lower edge of the gate in different positions of adjustment.

30 I fully realize that considerable variation in the construction and organization of the elements entering into my improvements is possible, without departing from the spirit of my invention, and I as fully

realize that it is utterly impossible to herein 35 illustrate all such; therefore I do not intend to limit myself to the specific constructions shown and described except as pointed out in the following claims, wherein it is my purpose to claim as broadly as is permitted 40 by the state of the art all the novelty inherent in the invention.

Having thus set forth the nature of the invention I claim as new the following, to-wit:

45 1. In a structure of the nature described, a stationary door-casing, a skeleton door-frame hinged to a vertical member thereof, a gate arranged to reciprocate vertically in the frame, a rack associated with the frame, 50 a latch carried on the gate and adapted for engagement with the teeth of said rack, and means for releasing the latch and simultaneously elevating the gate.

2. In a structure of the nature described, 55 a skeleton door-frame adapted to swing in a horizontal arc, a gate slidable vertically between the side-bars of said frame, a latch carried by the gate, a rack the teeth of which are adapted for engagement by said 60 latch, a pulley arranged at the upper end of the rack, and a rope traversing said pulley and connected with the latch to operate the same.

65 In witness whereof I hereto affix my signature at Galesburg, Illinois, this 9th day of March, 1916.

PERRY C. JAMES.
